ABSTRACT OF THE DISCLOSURE

This invention relates to a control system for controlling the delivery and discharge of workpieces or slabs into and from a furnace operative with a hot strip rolling mill. A computer may be utilized to control a pusher assembly to serially deliver one or more of the slabs from a furnace charging table onto the skids that run the length of the furnace. At the exit side of the furnace, the computer controls an extractor assembly to enter the furnace and to extract each slab to be delivered and to place it onto a delivery table. The slabs are disposed within the furnace in an abutting relationship so that as a slab is pushed from the furnace charging table and against the first slab in the series of slabs within the furnace, then the last slab in the furnace is pushed into a position where the extractor may withdraw it from the furnace. The computer has a capability for storing the dimensions of each individual slab and serves to control the distance the series of slabs are pushed to ensure that the last slab in the furnace is disposed in a position so that the extractor may readily take it from the furnace.

BACKGROUND OF THE INVENTION**Field of the invention**

This invention relates to a system for controlling the positioning of a plurality of workpieces or slabs, and more particularly to a system for controlling the entry and exit of each of a plurality of slabs to and from a furnace operative with a hot strip rolling mill.

Description of the prior art

In a typical hot strip steel mill, workpieces or slabs, which have been previously rolled from ingots or directly cast, are taken to the hot strip mill where they are converted through rolling from slabs to coils of steel strip. Typically, slabs are taken to the hot strip steel mill in piles where they are sorted and each arranged to be sent through a heating furnace in preparation to being rolled into a long strip. The slabs are taken from the furnace and are directed first through a roughing mill which may consist of a plurality of stands to successively reduce the thickness of the slab, and then through a finishing mill which further reduces the thickness of the elongated slab into a desired thickness. After passing through the finishing mill, the strip is then wound upon a coiler and taken from the mill.

More specifically, a pile of slabs may be taken to the mill where the slabs are deposited upon a receiving table. Next the pile of slabs is taken to a depiler assembly where the topmost slab is removed and the slabs placed one at a time onto the first furnace receiving table. A plurality of serially oriented furnace charging tables are provided to take the slabs individually from the depiler assembly and to position them so that they may be pushed into one of a plurality of furnaces. A suitable control system may be provided for accurately positioning each of the slabs upon a furnace charging table. The slabs come in a variety of ranges of length and are carefully

2

positioned in accordance with their respective lengths before they are placed in the furnace. A control system and a plurality of detectors can be provided so that the slabs may be disposed evenly within the furnace. The furnaces include a plurality of burners disposed evenly throughout the furnace and may heat each of the slabs to a temperature of approximately 2350° F. The heating process may require several hours to evenly heat each of the slabs throughout its thickness. The slabs are then taken from the furnace and are disposed in the finishing and roughing mills in order to reduce the thickness of the slabs and to form strips which are eventually coiled as explained above.

It has been typical of the prior art practice for the operator to effect the desired placement of the slabs into and from the furnace by manual control. It is normally not convenient to place the operator in a proximate position to the furnace charging tables or the furnace delivery tables such that the operator must normally view the placement of the slabs by means of television monitors. Illustratively, the slabs would be removed from the furnace by sliding the slabs downward from the furnace skids onto the delivery tables. The furnace delivery tables would be provided with bumpers to stop the slabs. Typically, the operator would view the placement of the slabs to be removed upon a television monitor and manually control a pusher to slide the entire row of slabs until the last slab slides onto the furnace delivery table. More recently, extractor assemblies have been developed for withdrawing slabs from furnaces. Typically, extractor assemblies serve to lift the slabs from the skids of the furnace and to place them on a furnace delivery table. The operation of the extractor assembly has been performed manually by an operator, who visually checks the movement of the extractor. It is particularly pointed out that such operations are time consuming and require much of the operator's time and attention.

It is therefore an object of this invention to provide a new and improved system for better controlling the delivery to and exit of slabs or workpieces from a furnace.

SUMMARY OF THE INVENTION

This and other objects are accomplished in accordance with the teachings of this invention by providing a new and improved slab control system including a pusher assembly for delivering a plurality of slabs one at a time into a furnace, an extractor assembly for removing a plurality of said slabs one at a time from the furnace and depositing them on a furnace delivery table from which they are sent to the roughing mill. The system of this invention may include a computer having the capability for storing the dimensions of each of the plurality of slabs and for controlling the stroke of the pusher relative to each slab so that the series of abutting slabs within the furnace are moved a distance corresponding to a width of the last slab. As a result, the last slab is disposed in an extracting position from which the extractor assembly, when desired, removes the slab from the furnace. The computer may also serve to control the placement of the slab to be removed by the extractor to position correctly the slab on the furnace delivery table.

DESCRIPTION OF THE DRAWINGS

These and other objects and advantages of the present invention will become more apparent when considered in view of the following more detailed description and drawings, in which:

FIGURE 1 is a side view of a furnace delivery and exit system in accordance with the teachings of this invention;

FIG. 2 is a plan view of a furnace charging table and

pusher assembly which may be incorporated within the system of FIG. 1;

FIG. 3 is a plan view of a furnace delivery table and an extractor assembly which may be incorporated within the system of FIG. 1;

FIG. 4 is a view of the assembly for lifting the extractor doors and the furnace exit doors for respectively allowing the extractors to enter and to extract slabs from the furnace of FIG. 1; and

FIG. 5 is a schematic diagram of a computerized control system for regulating the pusher assembly and the extractor assembly as shown in FIG. 1 in accordance with the teachings of this invention.

DESCRIPTION OF THE PREFERRED EMBODIMENT

Referring now to the drawings, and in particular to FIG. 1, there is shown an illustrative embodiment of a furnace delivery and extracting system 10 in accordance with the teachings of this invention. A plurality of slabs 40 are brought one at a time to a furnace charging table 12 and are positioned thereon so as to evenly charge a furnace 32. Then the slabs 40 are pushed from the furnace charging table 12 onto a plurality of skids 36 which run the length of the furnace 32. As shown in FIG. 1, the slabs 40 within the furnace 32 are disposed in an abutting relationship with the front edge of the leading slab 40a coinciding with an index line 44. As will be explained in greater detail later, a pusher assembly or displacement means 18 slides a slab 40 from the furnace charging table 12 onto the skids 36 to abut the trailing edge of the last slab 40n within the furnace 32. The pusher assembly 18 slides the entire line of slabs 40 a distance corresponding to the width W_1 of the leading slab 40a so that the leading slab 40a is then disposed in an extracting position 45 ready to be taken by an extractor assembly or displacement means 60 from the furnace 32 and deposited centrally upon a furnace delivery table 50. It may be understood that there may be a plurality of furnaces similar to furnace 32 disposed in parallel between a plurality of furnace charging tables and a plurality of furnace delivery tables. The furnace delivery tables transport the slabs 40 into the roughing and finishing mills where the thickness of the slabs is successively reduced.

A slab will be brought as explained above, from the depiler assembly to the furnace charging table preceding the furnace charging table 12 shown in FIGS. 1 and 2, where the slab 40 is held until it may be charged in furnace 32. The slab 40 upon command will be brought from the preceding charging table onto the furnace charging table 12 which includes a plurality of rollers 14 driven through a suitable gearing by a suitable drive motor (not shown). If the furnace 32 is in need of additional slabs, the slab 40 will be brought to its correct position with regard to the plurality of skids 36.

Once the slab 40 is correctly disposed upon the furnace charging table 12, the pusher assembly 18 is activated to slide the slab 40 from the furnace charging table 12 onto the skids 36. The pusher assembly 18 includes a pair of pushers 20, which are supported upon a plurality of rollers 28 to be driven in a reciprocal, rectilinear motion. Each of the pushers 20 includes a rack 21 whose teeth mesh with a pinion gear 30. The pinion gears 30 are connected to a drive shaft 22 (as shown in FIG. 2) which is driven by a pair of motors 24. As shown in FIGS. 1 and 2 each of the pushers 20 have a head assembly 25 from which are suspended a plurality of teeth 26 by pins 27. When the pushers 20 are driven forward, the teeth 26 will abut against the slab 40 to slide the slab 40 onto the skids 36. It is noted that the teeth 26 are suspended upon the pins 27 to allow the teeth to rotate counterclockwise as shown in FIG. 1 if they strike an object such as another slab upon their retracting cycle. As shown in FIG. 2, a suitable speed indicator 38 such as a tachometer is connected to the motors 24, and further, suitable position sensors

39 such as selsyn transmitters are connected to the drive shaft 22 to provide an output signal accurately indicating the position of the pushers 20. In addition, limit switches 41 are connected to the shaft 22 to generate an electrical signal indicating when the pushers 20 are disposed in their retracted position.

A slab 40 is slid from the furnace charging table 12 onto the skids 36 so that the leading edge of the slab 40 abuts the trailing edge of the slab 40n whose leading edge is disposed within the furnace 32. As shown in FIG. 1, the furnace 32 has an entrance door 34 which is disposed in an open position to allow the slabs 40 to be slid therethrough. In order to help explain the operation of this system, the slabs 40 have been designated with suffixes 5 to 25 to designate their position within the furnace 32. More particularly, the slab 40a has its leading edge disposed upon the index line 44. Slab 40_{n-1} is that slab being pushed from the furnace charging table 12 onto the skids 36, and slab 40n is that slab with its leading edge within the furnace 32 and against which the slab 40_{n-1} is to be pushed. As shown in FIG. 1, the leading edges of the slabs 40 abut the trailing edge of the next slab 40 so that if slab 40n is pushed the following slabs will be pushed forward so that slab 40a will be disposed in the extracting position 45.

As the slab 40a is being disposed in the extracting position 45, the sets of furnace exit doors 46 and extractor doors 48 are lifted upwards, and the extractor assembly 60 is activated to move to the left as shown in FIG. 1, 30 to extract the slab 40a, and to deposit it centrally upon the furnace delivery table 50. As shown in FIGS. 1 and 3, the furnace delivery table 50 includes a plurality of rollers 52 and a table motor 58 for driving through a reducer 56 and appropriate gearing 54, the rollers 52. The 35 extractor assembly 60 includes a plurality of extractors 62, which as shown in FIG. 3, extend between the rollers 52 of the furnace delivery table 50, and which are driven into the furnace 32 through the doors 48 by a pair of 40 traverse motors 92. Normally, the traverse motors 92 are 45 interconnected through shafts 97 and a magnetic clutch 95. However, when it becomes necessary to extract a pair of double row slabs 40, one of the motors 92 may be energized to insert one of the extractors 62 to withdraw one of the pair of slabs, and then the other traverse motor 92

may be energized to remove the other slab 40. As shown more clearly in FIG. 1, each of the extractors 62 includes a drive extension 64 to which is secured a rack 66. The teeth of the rack 66 mesh with the teeth of a pinion gear 68. The pinion gears 68 are in turn driven by a drive shaft 69. As shown in FIG. 3, the drive shaft 69 is connected to the motors 92 by reducer gearings 94. When the traverse motors 92 are energized, the drive shaft 69 will be driven to displace the extractors 62 in a substantially rectilinear motion. Each extractor 62 includes 55 an extractor finger 70 which may be driven to the right as shown in FIG. 1 between the rollers 52 and into the furnace 32. Suitable rollers 71 and 73 are provided for directing and confining the rectilinear motion of the drive extensions 64 along a substantially linear path. Further, 60 suitable sets of wheels 72 are rotatably connected to each of the extractors 62 to allow the extractors 62 to be rolled forward upon a lift assembly 74. As shown more clearly in FIG. 3, suitable speed detectors 96 such as tachometers are connected to each of the traverse motors 92, and suitable 65 positioning detectors 98 such as selsyn transmitters are connected to the traverse motors 92 to provide electrical signals indicative of the position of the extractors 62. Further, the drive shafts 69 are connected to limit switches 75, which generate signals indicative of when the extractors 62 are in their fully extended position.

As seen more clearly in FIG. 1, the traverse motors 92 drive the extractor 62 in a rectilinear motion forward into the furnace 32 upon the wheels 72. The wheels 72 roll upon the lift assembly 74 which may be raised and lowered by a pair of lift motors 88. As shown in FIG. 3,

the lift motors 88 are interconnected by shafts 81 to a magnetic clutch 83. The magnetic clutch 83 allows the lift motors 88 to be operated separately to extract one of a pair of slabs from the furnace 32. Further, the lift motors 88 are connected to gearing mechanisms 78, which drive rotating members 80. As shown in FIG. 1, the lift assembly 74 includes a lift platform 76, which is pivotally connected to a pair of idler arms 82 and 84. The other ends of the idler arms 82 and 84 are also pivotally connected to a support or base member. A connecting rod 86 is eccentrically attached at one end to the member 80 by a suitable pin and fastened at the other end pivotally to the lift platform 76. When the connecting rod 86 is driven forward by the member 80, the lift platform 76 is pushed to the left as shown in FIG. 1, and the idler arms 82 and 84 are rotated counterclockwise (as shown in FIG. 1) to thereby lift the platform 76 upward. When the lift platform 76 is in its first or down position, the extractors 62 may be driven forward and into the furnace 32 without interfering with the slabs to be disposed upon the furnace delivery table 50. More specifically, as shown in FIG. 1, the height of the extractor fingers 70 is below the upper surface of the rollers 52 of the furnace delivery table 50. As shown in FIG. 3, suitable limit switches 90 are connected to the lift motors 88 to provide an electrical signal indicating when the lift platform 76 is in a second or up position. Further, a suitable interlock mechanism may be connected to the limit switches 90 to prevent the table motor 58 from driving the rollers 52 of the furnace delivery table 50 when the lift platform 76 is in up position.

Referring now to FIG. 4, a door motor 100 is provided for raising the extractor doors 48 and the exit doors 46 to allow the extractors 62 to enter the furnace 32 and to withdraw the slab 40a. More specifically, the door motor 100 is connected through a reducer gearing 102 to a drive shaft 104. Pluralities of wheels 110 and 111 are fixedly secured to the drive shaft 104 for respectively raising and lowering the extractor doors 48 and the furnace exit doors 46. Suitable flexible linkages 108 and 109 are respectively interconnected between the doors 48 and the wheels 110, and the doors 46 and the wheels 111. In addition, a suitable limit switch 106 is connected to the drive shaft 104 to provide an indication of when the doors 46 and 48 are opened or closed.

Referring now to FIG. 5, there is shown a control system 112 for delivering and extracting a plurality of slabs 40 into and from the furnace 32. The control system illustratively includes a computer 114 which in one embodiment serves to control the stroke of the pushers 20 to place the slab 40a in the extracting position 45 and also to control the withdrawal stroke of the extractor assembly 60 to precisely position the slab 40a upon the furnace delivery table 50. The dimensions and other characteristics of the slabs 40 are fed into the computer 114 by an input card reader 118. Typically, a card with the dimension data of a slab 40 is placed in the order of its processing into the card reader 118, which transfers this information into a storage facility within the computer 114.

The computer 114 functions to supply data corresponding to the widths of slabs 40 to the various position controls associated with the pusher assembly 18 or the extractor assembly 60. As discussed with reference to FIG. 2, a pair of pushers 20 are driven by the motors 24 through the drive shafts 22, which are connected to the position sensors 39. Further, the speed detectors 38 are connected mechanically to the pusher motors 24. An output signal indicative of the speed of the motors 24 is developed by the speed detectors 38 and is applied to a pusher regulator 124. In a similar manner, a signal indicative of the position of the pushers 20 is applied by the position sensor 39 to a position control circuit 116. As will be explained later, the computer 114 may initiate the operation of the pusher motors 24 and the control stroke through which the motors 24 drive the pushers

5 20. The position control 116 in turn applies a signal to the pusher regulator 124 indicative of the desired stroke or movement of the pusher 20. The pusher regulator 124 determines the speed of the pusher motors 24 by regulating the potential supplied by a power supply 126 to the pusher motors 24. The output of the speed detector 38 is applied to the pusher regulator 124 to complete a feedback control loop to ensure that the pushers 20 are being driven at the correct speed. In addition, a manual control 125 may be connected to the pusher regulator 124 whereby an operator may override the commands of the computer 114 and control manually the speed of the pushers 20. In addition, a manual initiate control 122 may be applied to the position control 116 to allow the operator to manually control the position of the pushers 20. As will be explained in detail later, the pushers 20 may be operated in a semi-automatic mode, wherein the operator may apply an appropriate signal developed by a semi-auto control 120 into the position control 116 to control the stroke of the pushers 20. Illustratively, the semi-auto control may include a decade switch to supply to position control 116 a binary signal indicative of the width W_1 of the slab 40a to be pushed.

25 As described above, the traverse motors 92 drive a shaft 69 to impart a rectilinear motion to the extractors 62. More specifically, the extractors 62 are driven to the left as shown in FIG. 1 into the furnace 32 and then after being lifted upon the platform 76 are withdrawn a given distance dependent upon the width W_1 of the slab 40a to be deposited upon the furnace delivery table 50. The computer 114 may serve to initiate the forward stroke of the extractor 62 and also the withdrawal of the slab 40a upon the extractor assembly 60. A signal may be supplied by the computer 114 to a position regulator 128 to initiate the operation of the motors 92 and to provide an indication of the width W_1 of the slab 40 to be withdrawn. In turn, the position regulator 128 applies an operating signal to a traverse regulator 130, which in turn controls the potential applied by a power supply 132 to the traverse motors 92. It is understood that the traverse motors 92 may be of the variable voltage type, whose speed is dependent upon the potential supplied thereto by the power supply 132. In the alternative, the traverse regulator 130 and the power supply 132 could be replaced by a constant voltage source with contactors controlled by the position regulator 128.

30 40 45 The speed detectors 96, which are connected to the traverse motors 92, generate and apply output signals indicative of the speed of the extractors 62 to the traverse regulator 130. The feedback control loop formed by the speed detectors 96 ensure that the slabs 40 are withdrawn at the correct speed. In addition, the position sensors 98, which are connected as shown in FIG. 3 to the motors 92, provide an output signal which is indicative of the position of the extractors 62. The position indicating signal is fed back to the position regulator 128, which compares the position indicating signal derived from the position sensors 98 with the slab width signal derived from the computer 114 to generate a difference or error signal for accurately positioning the slabs 40 upon the furnace delivery table 50. In addition, a manual control 131 may be provided to allow the operator to manually position the extractors 62. Further, a semi-auto control 129 may be provided to replace the slab-width signal derived from the computer 114. More specifically, the semi-auto control 129 may take the form of a decade switch to provide a binary signal indicative of the width of the slabs to be placed on the furnace delivery table 50.

50 55 60 65 70 75 Further, the position regulator 128 serves to initiate the operation of the lift motors 88. The lift motors 88 are mechanically connected as shown in FIGS. 1 and 3 to the driving members 80 which in turn are connected to lift the platforms 76. As shown in FIG. 1, when the leading edge of the extractor fingers 70 approach the index line 44, the maximum stroke of the extractor 62

has been reached. At this point, the position regulator 128 in response to the position signals derived from the limit switch 75 (or the position sensor 98) initiates the lift motors 88. More specifically, the position regulator 128 applies an appropriate operation signal to a raise and lower initiate control circuit 134. The control circuit 134 in turn applies a control signal to a constant voltage controller 136 which applies an appropriate constant voltage to the lift motors 88. Illustratively, the lift motors 88 may be constant voltage motors, whose operation is controlled by the constant voltage controller 136. As more specifically shown in FIG. 3, the limit switches 90 are connected to the motors 88 to provide an indication of when the lift platform 76 is in its up position. When the up position is reached, the limit switch 90 provides a feedback signal to the constant voltage controller 136 to stop the operation of the lift motors 88. As the lift platform 76 is raised, the extractor fingers 70 are raised up through the skids 36 to lift the slab 40a from the skids 36. At this point, the lift motors 88 are stopped, and the extractor assembly 60 withdrawn.

In order to insert the extractor fingers 70 within the furnace 32, the extractor doors 48 and the furnace doors 46 must be lifted at approximately the same point in time that the pusher assembly 18 is activated to push the line of slabs 40a to 40n into and through the furnace 32 and that the extractor assembly 60 begins to insert the extractors 60 into the furnace 32. More specifically, an initiate signal is applied to a constant voltage controller 140 which applies an appropriate voltage to the motor 100. As shown in FIG. 4, the motor 100 rotates the shaft 104, which in turn lifts the doors 46 and 48. As shown in FIG. 5, a manual control 142 allows the operator to manually lift the doors 46 and 48. The limit switch 106 is connected to the shaft 104 and when the doors 46 and 48 have reached their up position, the limit switch 106 applies a feedback control signal to the constant voltage controller 140 to stop the door motor 100. Further, it is noted the limit switch 106 provides an interlock with the position regulator 128 to prevent the extractor assembly 60 from being driven to the left as shown in FIG. 1 by the traverse motors 92 when the doors 48 and 46 are in their down position.

In preparation to operating the furnace delivery and exit system 10 in an automatic mode, a plurality of slabs 40 are brought one at a time to the furnace charging table 14 and pushed into the furnace 32 until the furnace has been filled. Additional slabs 40 will be pushed into the furnace 32 until the first or leading slab 40a is brought to the position where its leading edge coincides with the index line 44. As shown in FIG. 1, a detector 42, which may take the form of a television camera, allows the operator to manually position the line of slabs so that the leading edge of the slab 40a to be discharged is on the index line 44. It is noted that an auto-initiate control circuit 144 is a part of the control system 112 and may illustratively include a suitable clock mechanism for initiating the various processes of the system at desired times. In addition, the auto-initiate circuit 144 allows the operator to begin the process whereby the slab 40 is taken from the furnace delivery table 12 and placed into the furnace 32, while the extractor assembly 60 is extracting a slab from the furnace 32 and placing it on the furnace delivery table 50.

After the leading edge of the slab 40a has been disposed on the index line 44, the operator manually brings the pushers 20 until its teeth 26 abut the trailing edge of the slab 40n. Then the operator either through the auto-initiate circuit 144 or the computer 114 causes the computer 114 to interrogate the position sensor 39, through the position controller 116, to determine the encoder position of the shaft 22 and therefore the pushers 20. The computer 114 will then command the pusher motors 24 to retract the pushers 20 to their full retract position, i.e. the position shown in FIG. 1. As the pushers 20 approach

their full retract position, the limit switch 41 will provide a feedback signal to the position control 116 to thereby stop the pusher motors 24. The computer 114 will again interrogate the position sensor 39 to determine its encoder position with the pushers 20 in their retracted position. Knowing the two encoder positions of the sensor 39, the computer 114 will then know the open skid space available. The open skid space is that space between the edge of the furnace charging table 14 and the trailing edge of the slab 40n. The pushers 20 will remain in the retract position until the computer 114 gives it the command to go forward to park or to push the slabs 40.

Due to the fact that the slab width is constantly changing in random pattern, there will be many cases when more than one slab must be charged for each slab delivered. In other case, multiple slabs will have to be delivered for each slab to be charged. For this reason, when the furnace delivery and exit system 10 is being operated in the automatic mode, the computer 114 will determine after each charging round whether or not there is sufficient room to park another round of slabs before pushing. In other words, it is desired to keep the skids 36 as full as possible at all times without blocking the furnace charging table 12. When a slab 40 has been brought to the furnace charging table 12 and has been parked, the pushers 20 will remain across the furnace charging table 12 to wait for the signal to push the first slab 40a to the extractor position 45. Other slabs 40 may now pass under the pushers 20 to the other furnaces. Next, the computer 114 interrogates the position sensor 39 to determine, the distance the pushers 20 may advance the slabs 40 in the furnace 32, which distance is denoted by the letter X in FIG. 1. As explained above, the width of each of the slabs 40 in the furnace is stored within the memory of the computer 114. In preparation to pushing the slabs 40, the computer 114 determines whether the distance X is equal to or greater than the width W₁ of the slab 40a to be delivered. If the dimension X is greater than W₁, the control system 112 is prepared to push the series of slabs 40 through the furnace 32 to thereby place slab 40 in the extractor position 45. It is understood that the time of delivery to the delivery furnace table 50 may be determined by the schedule of the finishing and roughing mills, and that the same computer 114 may serve to control the functions of the finishing and roughing mills. Thus, when an additional slab is needed for the mills, the computer 114 will initiate the pushing operation and as will be explained, the sequencing of the extractor assembly 60 and the lift assembly 74. If the computer 114 determines after the slab 40_{n-1} has been parked, that the dimension X is less than the width W₁ of the slab 40a, the computer 114 will not allow the pushing cycle to be commenced until another slab 40 has been parked upon the skids 36.

When the slabs directed to the next furnace have been cleared of the furnace charging table 12, and the next slab is brought up to the furnace charging table preceding table 12, one of two conditions may exist. First, the furnace 32 may have already pushed slab 40a to the extractor position 45 and have withdrawn the pusher 20 to the retracted position. In this case, the new slab will come to rest upon the furnace charging table 12 and be pushed onto the skids 36. However, the slab 40a may not have been delivered to the extractor position 45 since the last slab 40 was placed upon the skids 36. In this case, the computer 114 interrogates the position sensor 39 to determine whether the distance X is equal to or greater than the slab width W₁ of the slab 40a to be pushed to the extractor position 45. If as determined by the computer 114 the dimension X is not equal to or greater than the width W₁, the pushers 20 are retracted and the new slab 40 will be positioned upon the furnace charging table 12, to be pushed upon the skids 36. If however, the dimension X is equal to or greater than the width W₁ of the slab 40a to be delivered, the computer 114 must look

to see how much time remains before the slab 40a is to be extracted from the furnace 32. The extractor assembly 60 requires a certain amount of time to extract the slab 40a and to place it upon the furnace delivery table 50. If the time before the next slab 40a is to be delivered is equal to or greater than the required delivery time, i.e. in the order of 30 seconds, as determined by a clock mechanism within the computer 114, the pushers 20 will be withdrawn, and the new slab will be positioned upon the furnace charging table 12 and pushed upon the skids 36. It is particularly noted that the dimension X is updated by the computer 114 each time a slab is to be pushed. It is noted that there is a limit to the aggregate width of slabs that may be disposed upon the skids 36. The slabs 40 may be continued to be parked upon the skids 36 and until the trailing edge of the last slab to be parked interferes with the travel of the slabs down the furnace charging tables. In order to prevent the dimension X from increasing to the point where the furnace charging table 20 will be blocked, the computer must insure that the pusher assembly 18 is operated in order to remove the slab 40a or in the alternative, to stop the on-coming slabs on the furnace charging table preceding table 12.

Any random difference in the total width of the slabs in one furnace with respect to the other furnaces, may cause trouble which may be taken care of by the insertion of a dummy slab.

During the operation of this system in an automatic mode, the operator should occasionally check the position of the leading edge of the slab 40a to be delivered with respect to the index line 44. When the operator discovers that the index line 44 is drifting with respect to the leading edge of slab 40a, the operator should manually advance the pusher 20 to correctly position the leading edge of the slab 40a with respect to the index line 44 and then to manipulate the computer to recalibrate the clear space as explained above.

In preparation to operating the extractor assembly 60, the extractors 62 are driven to their maximum extended position in which the extractor fingers 70 are disposed to lift the slab 40a to be delivered, and the computer 114 interrogates the position sensor 98 (through the position regulator 128) to determine the encoder position of the fully extended extractor assembly 60. When the furnace delivery table 50 is ready to receive the next slab from the furnace 32, an initiate signal is derived either from the auto initiate control 144 or the computer 114 to start the pushing cycle of the pusher assembly 18. When the pushers 20 have been extended a distance sufficient to push the series of slabs a distance corresponding to the width W_1 of the slab 40a to be extracted, a feedback signal is developed by the position sensor 39 and applied to the position regulator 128. The position regulator 128 compares the feedback signal with the input signal derived from the computer 114 and indicative of the width W_1 to generate an error signal. When the error signal equals zero, the position control 128 will stop the operation of the pushers 20. Now, the slab 40 will have been disposed in the extract position 45 and the slab 40b will be repositioned so that its leading edge coincides upon the index line 44.

At the same time, the pushing cycle is commenced an initiate signal is given to the extractor assembly 60 to start an extracting cycle and also to the constant voltage control 140 to raise the extractor doors 48 and the furnace exit doors 46. When the doors 46 and 48 have been lifted to their up position, the limit switch 106 applies a feedback signal to the constant voltage controller 140 to stop the operation of the motor 104. At the same time the doors 46 and 48 are being raised, the position regulator 128 initiates the operation of the traverse motors 92 to drive the extractors 62 toward and into the furnace 32. As noted in FIG. 1, the height of the extractor fingers 70 during the initial thrust is below the height of

the rollers 52, so that the fingers 70 will not interfere with the slab in the extract position as the extractor moves into the furnace. When the extractors 62 are fully extended within the furnace 32, the limit switch 75 provides a feedback signal to the position regulator 128, which causes the motors 92 to stop. It is noted that a similar signal could be developed by the position sensor 98. In addition to stopping the motors 92, the position regulator 128 provides an initiate signal to the automatic raising and lowering initiate control 134, which in turn starts the lift motors 88 to raise the lift platform 76. As the lift platform 76 is driven upward, the extractor fingers 70 contact and lift the slab 40 from the skids 36. When the lift platform 76 has reached its upper position, the limit switch 90 will provide a feedback signal to the constant voltage controller 136 to stop the lift motors 88 and also to the position regulator 128 to initiate the withdrawal of the extractor 62.

With reference to FIG. 1, it is desired to place slab 40a upon the furnace delivery table 50 so that the centerline of the slab 40a coincides approximately with a centerline 51 of the furnace delivery table 50. As explained above, the width of each of the slabs 40 in the furnace 32 are stored in the memory section of the computer 114. As the slab 40a is being withdrawn by the extractor 60, a position signal is generated by the position sensor 98 and applied to the position regulator 128, which compares this position signal with a signal developed by the computer 114 indicative of the desired placement of the slab 40a upon the furnace delivery table 50. The slab 40a is withdrawn upon the extractor 62 a distance equal to the spacing between the index line 44 and the centerline 51 minus $\frac{1}{2}$ the width W_1 of slab 40a. When the error signal developed within the position regulator 128 equals approximately zero, the position regulator 128 causes the traverse motors 92 and the extractor assembly 60 to stop and then applies a lowering initiate signal to the control 134. In turn, the automatic raise and lower initiate control 134 starts the lift motors 88 to therefore lower the lift platform 76. When the lift assembly 76 reaches its lower position, the limit switch 90 provides a feedback signal to the controller 136 to stop the lift motors 88. At this point with the lift platform 76 in its lowered position, the slab 40a has been disposed upon the furnace delivery table 50 within its centerline coinciding with the centerline 51 of the table 50. It is noted that the limit switch 90 connected to the lift motors 88 may also provide an interlock to the motor 58 driving the furnace delivery table 50. Thus when the lift assembly 76 is in an up position, the motor 58 is prevented from operating and when the lift platform 76 is down, the motor 58 is allowed to drive the rollers 52 of the table 50.

When the double row slabs are being extracted, they will be pushed together, but will be extracted one at a time by the extractor assembly 60. The computer 114 may be used to control the magnetic clutch 95 to operate the extractors 62 separately.

The furnace delivery system 10 may also be operated in the semi-automatic mode. As in the automatic operation, the pushers 20 and the extractors 62 are calibrated in their extended and retracted positions. Instead of relying upon the computer 114, the operator would note the encoder signals from the position sensors 39 and 98. First, a slab 40 would be delivered to the furnace delivery table 12 and would be positioned either manually or automatically. Then the operator manually operates the pushers 20 to slide the slab 40_{n-1} upon the skids 36 so that it is in contact with the slabs 40 already on the skids 36. Next, the operator takes a look at a display derived from the camera 42 to check that the leading edge of the slab 40a to be discharged is disposed upon the index line 44. The pushers 20 are now left in this position, while the operator determines the width W_1 of the slab 40a to be extracted and sets the width W_1 into the semi-automatic controls 120 and 129. As explained above, the controls 120 and

129 may include decade switches into which may be set accurately the width W_1 of the slab 40a. When it is desired to extract the slab 40a, the operator will initiate simultaneously through the semi-auto controls 120, 129, a push cycle and a retract cycle. Upon the actuation of these controls, the furnace exit extractor doors 46 and 48 will be drawn upward by the motor 100 until the limit switch 106 applies a feedback signal to the control 140 to stop the motor 100. At the same time, the extractors 60 are driven into the furnace 32 until the limit switch 75 causes the traverse motors 92 to stop. At the same time, the pushers 20 are driven forward by the pusher motors 24 a distance W_1 corresponding to the width of the slab 40a to be extracted. As the pushers 20 complete their stroke, the position sensor 39 provides a feedback signal to the position control 116, which compares this feedback signal with the input signal derived from the control 120 to provide an error signal which will be fed to the position regulator 128. When a zero error signal is obtained from the position control 116 and a feedback signal is derived from the limit switch 106 indicating that the doors 46 and 48 are in a raised position, the position regulator 128 will initiate through the control 113, the raising of the lift platform 76 and therefore the extractor 62. At the same time the position control 116 derives a zero error signal, the position control 116 will also retract the pushers 20. When the lift platform 76 is raised and the furnace exit doors 46 are open, the extractors 62 will be withdrawn from the furnace 32 to position the slab 40a on the centerline 51 of the furnace delivery table 50. The extractors 62 will be withdrawn a distance equal to the spacing between the index line 44 and a centerline 51 minus $\frac{1}{2}$ the width W_1 of the slab 40. The positioning of the extractor 62 will be controlled by the position control 129, which compares the feedback signal derived from the position sensor 98 with a reference signal derived from the control 129. The furnace exit doors 46 will be closed when the extractors 62 have cleared the door 46. Finally, the extractor 62 will lower the slab 40 onto the furnace delivery table 50. At this point, both the extractors 62 and the pushers 20 will be in position for the next cycle when the operator desires to initiate it.

Since numerous changes may be made in the above described apparatus and different embodiments of the invention may be made without departing from the spirit thereof it is intended that all matter contained in the foregoing description are shown and the accompanying drawings shall be interpreted as illustrative and not in a limiting sense.

I claim as my invention:

1. A system for controlling the movement of slabs relative to a furnace including first support means for receiving at least one of said slabs, first displacement means for delivering at least one said slab from said first support means into said furnace, second displacement means for extracting at least said one slab from said furnace, second support means upon which said second displacement means deposits at least said one slab, and control means into which at least one dimension of at least said one slab may be set to determine the displacement imparted to at least said one slab by both said first and second displacement means.

2. A control system as claimed in claim 1, wherein there is included first detecting means for sensing the displacement imparted to at least said one slab by first displacement means, and second detecting means for sensing the displacement imparted to at least said one slab by said second displacement means.

3. A control system as claimed in claim 2, wherein said first and second detecting means develop respectively first and second output signals indicative of the displacements imparted to at least said one slab by first and second displacement means, said control means comparing

said first and second output signals with said one dimension to thereby determine the displacement imparted to at least said one slab by both of said first and second displacement means.

4. A control system as claimed in claim 3, wherein said control means includes a computer having a program storage capability for storing said one dimension of at least said one slab.

5. A control system as claimed in claim 4, wherein said control means includes first and second position controls for controlling the position respectively of said first and second displacement means, said computer applying output signals indicative of said one dimension of said slab to said first and second position controls, said first and second detecting means applying respectively said first and second output signals to said first and second controls, said first and second position controls comparing the signals derived from said computer with said first and second output signals to thereby control the placement of at least said one slab.

6. A control system as claimed in claim 1, wherein each of said slabs is disposed in the line on third support means disposed within said furnace, said first displacement means pushing said line of slabs so that the first slab of said line is disposed in an extract position, said second displacement means including extractor means, extractor drive means suitably connected to said extractor means for disposing extractor means within said furnace, lift means associated with said extractor means, and second suitable drive means for lifting said lift means and said extractor means to thereby displace each of the slabs disposed within said furnace support means.

7. A control system as claimed in claim 6, wherein a first position sensor is associated with said extractor means for providing a first output signal indicative of the position of said extractor means, and a second position sensor associated with said lift means for providing a second output signal indicative of the position of said lift means.

8. A control system as claimed in claim 7, wherein said control means includes position control means for controlling the operation of said extractor drive means, said first position sensor applying said first output signal to said position control means, said position control means comparing said first output signal with said one dimension of the slab to be disposed in said extract position to control the displacement imparted by said extractor means to the slab to be extracted so that the slab to be extracted is disposed upon said second support means.

9. A control system as claimed in claim 8 wherein said second position sensor provides that said second output signal indicates that said extractor means is in an extended position and applies said second output signal to said position control means, said position control means initiating the operation of said lift drive means to raise said lift means.

10. A control system as defined in claim 6, wherein there is included at least one door through which said extractor means is disposed into said furnace, and door drive means associated with said door to selectively raise and lower said door.

11. A control system as claimed in claim 10, wherein said control means simultaneously initiates the pushing of said line of said slabs, the movement of said extractor means into said furnace, and the opening of said door.
